215,235

FLOOR LAMP BASE

Morris Lange, Shaker Heights, Ohio, assignor to Superior Funeral Supply Corporation, Cleveland, Ohio, a corporation of Ohio

Filed June 26, 1968, Ser. No. 12,505

Term of patent 14 years

Int. Cl. D26—02

U.S. Cl. D48—20

Fig. 1

Fig. 2

FIGURE 1 is a perspective view of a floor lamp base embodying my new design, the opposite sides not shown, being substantially mirror images of the sides shown; and,

FIGURE 2 is an enlarged cross-sectional view taken on the line 2—2 of FIGURE 1.

I claim:

The ornamental design for a floor lamp base, as shown and described.

References Cited

UNITED STATES PATENTS

D. 75,555	6/1928	Gedgaud	-----	D48—20
D. 148,376	1/1948	Math.
D. 202,438	9/1965	Lange.
		1,431,670	10/1922	Klein.

WALLACE R. BURKE, Primary Examiner

SUSIE J. MERCER, Assistant Examiner